Primary Examiner — Susan E Krakower*Assistant Examiner* — Lisa A Grabenstetter(74) *Attorney, Agent, or Firm* — Wang Law Firm, Inc.(57) **CLAIM**

The ornamental design for a combined hair brush and comb, as shown and described.

DESCRIPTION

FIG. 1 is a front view of a combined hair brush and comb, showing my new design;

FIG. 2 is a back side view thereof;

FIG. 3 is a left side view thereof;

FIG. 4 is a right view thereof;

FIG. 5 is a top plan view thereof;

FIG. 6 is a bottom plan view thereof;

FIG. 7 is a perspective view thereof;

FIG. 8 is an enlarged front view of the comb feature from the end of the brush;

FIG. 9 is an enlarged back side view thereof;

FIG. 10 is an enlarged left side view thereof;

FIG. 11 is an enlarged right view thereof;

FIG. 12 is an enlarged top plan view thereof;

FIG. 13 is an enlarged bottom plan view thereof;

FIG. 14 is an enlarged perspective view thereof; and,

FIG. 15 is an exploded view of the hair brush and comb feature.

The broken line in FIG. 15 represents an unclaimed portion of the brush handle.
